CLAIM

The ornamental design for a display screen for aerosol generation device with graphical user interface as shown and described.

DESCRIPTION

FIG. 1 is a front view showing a first image of a display screen for aerosol generation device with graphical user interface according to the present design.

FIG. 2 is a partially enlarged front view of FIG. 1.

FIG. 3 is a front view of a second image thereof.

FIG. 4 is a partially enlarged front view of FIG. 3.

FIG. 5 is a front view of a second image thereof; and,

FIG. 6 is a partially enlarged front view of FIG. 5.

The subject matter in this patent includes a process or period in which an image changes into another image. This process or period forms no part of the claimed design.

The short dash long dash lines depict the display screen for aerosol generation device and form no part of the claimed design.

The broken lines within the short dash long dash lines depicts parts of the graphical user interface that form no part of the claimed design.

The dot dash lines in the drawings represent a boundary line and form no part of the claimed design.

All other broken lines in the figures depict the environment of the aerosol generation device and form no part of the claimed design.
